UNITED STATES PATENT OFFICE.

JOHN BILLARD, OF HONESDALE, PENNSYLVANIA, ASSIGNOR TO T. B. CLARK & CO., OF SAME PLACE.

DESIGN FOR THE ORNAMENTATION OF GLASSWARE.

SPECIFICATION forming part of Design No. 20,570, dated March 10, 1891.

Application filed February 3, 1891. Serial No. 380,092. Term of patent 14 years.

To all whom it may concern:

Be it known that I, JOHN BILLARD, of Honesdale, in the county of Wayne and State of Pennsylvania, have invented and produced 5 a new and original Design for the Ornamentation of Glassware, of which the following is a specification, and which is shown in the accompanying drawings.

The drawings represent in Figure 1 a plan 10 view of the inside of a glass bowl formed according to my said design. Fig. 2 shows a central vertical section of the same on line *x* of Fig. 1.

The main feature of the design consists of 15 grooves running from margin to margin of the design at right angles to each other and crossing each other at the center of the bottom and other grooves running also from margin to margin aside from the center. The 20 grooves first mentioned are marked *aa*. They are double grooves, leaving a rib between, and the double grooves diverge from each other as they approach the margin, so that the rib is gradually widened. The lines aside from 25 the center are shown at *bb*. These are also preferably double lines, forming a rib between them, and they cross the lines *a* to form there-

with an equal angle on both sides in corresponding position. Another set of lines, also shown double and turned still farther aside 30 from the center, are extended from the lines *bb* at the margin thereof to the other extremity of the same lines to the other margin of the lines, and these are marked *c*. There are two sets of these, each crossing the other. 35 The third set of lines (marked *d*) extend near the margins of the design, also shown double, and each of these double lines extends from the widened rib between the lines *aa* to the next corresponding rib. These lines cross the 40 rib and cut it.

The margin of the design is ornamented or formed in the ordinary way. The larger subdivisions formed by the intersection of the lines are also ornamented suitably. 45

I claim as my invention—

A design for glassware, substantially as herein shown.

In testimony whereof I affix my signature in presence of two witnesses.

JOHN BILLARD.

Witnesses:

W. H. STONE,
JOS. F. CRANDALL.
